UNITED STATES PATENT OFFICE.

JAMES T. SMITH, OF NEWARK, NEW JERSEY.

MANUFACTURING LEATHER.

969,570.

Specification of Letters Patent. Patented Sept. 6, 1910.

Application filed January 18, 1910. Serial No. 538,668.

To all whom it may concern:

Be it known that I, JAMES T. SMITH, a citizen of the United States, residing at Newark, in the county of Essex and State of New Jersey, have invented certain Improvements in the Art of Manufacturing Leather, of which the following is a specification.

This invention relates to the setting-out, stretching and finishing of leather in the course of its manufacture, the setting-out and stretching being done by the improved method shown and described in my prior application, Serial No. 512,312, filed August 11, 1909, or a modification thereof herein described.

The objects of the present invention are to save labor and time in japanning or otherwise finishing leather; to obviate the necessity for tacking the leather upon a japanning frame; to prevent waste due to perforating the edges of the leather; to secure a firm rigid support for the leather during the finishing operations; to thus secure a more perfect japanning or other finishing of the leather; to firmly secure the leather to the surface on which it is set-out in its stretched condition, and to obtain other advantages and results as may be brought out in the following description.

Referring to the accompanying drawings, in which like numerals of reference indicate corresponding parts in each of the several figures, Figure 1 is an end edge view of a bed or support upon which the first half or portion of a piece of leather is being set-out on a setting-out board according to my invention, and Fig. 2 is a similar view of the last half or portion of the leather being set-out; Fig. 3 shows in plan the setting-out board with the leather dried thereon as set-out and adhering thereto, and ready for japanning or other finishing while still set-out and adhering to the board, and Fig. 4 is an elevation of the same.

In said drawings, 10 indicates a flat smooth bed of suitable hardness and solidity to serve as a support for the setting-out board 12 while the leather 13 is being set-out thereon. In doing this the setting-out board is first laid upon the bed 10, as shown in Fig. 1, with one of its longer edges substantially even with the front edge of said bed, said board being preferably thin and flat with smooth hard opposite sides or faces upon which the leather can be set-out,

as fully described in my prior application above referred to. Preferably one-half of the leather 13 is first set-out upon the upper side of the board 12, the other half hanging down between the operator and the table as shown in Fig. 1. Then the setting-out board 12 is turned over and the other half of the leather set-out on its opposite side or face, as shown in Fig. 2, the leather being thus bent or doubled over one edge of the setting-out board. This setting-out of the leather upon the board 12 leaves it adhering thereto in a stretched condition, and by my improved process set forth in the prior application above referred to the leather is dried with its relation to the board undisturbed, that is to say, while still upon the board and adhering thereto as set-out. The leather is then ready for japanning, or any of the other similar finishing processes known to the trade, it being understood that my present invention relates to all such finishing processes and that I mean to include them all even though I say for definiteness and simplicity "japanning" only.

It will be understood that in finishing leather heretofore in the art, the leather, usually in pieces the full size of the hide, has been secured in a rectangular japanning frame by means of tacking the edges thereto where they overlapped, and securing them elsewhere by strings. In this position, the various coatings have been applied in turn to the leather and worked in as perfectly and evenly as possible with the leather in such loose yielding condition. Then the frame with the leather on it has been stood up to dry such coatings.

By my improved process I japan or otherwise similarly finish the leather while still adhering to the board 12 upon which it has been set-out and dried, and not until such finishing process is completed and the leather again dried, is it removed from or pulled off of the setting-out board 12. The great advantages of doing this are that the various coatings employed in finishing are applied to the leather while it is rigidly held in position by the setting-out board, and the advantage of this is twofold, first the coatings can be applied with great facility because the leather is thus firmly and rigidly held, and second the coatings are applied much more evenly because the leather is perfectly flat and there are no depressions or hollows in which they can collect, and thus a

more perfect and higher grade product is obtained.

During the japanning or other finishing of the leather while still set-out upon and adhering to the setting-out board, said setting-out board may be supported or held in any convenient manner, but preferably so that the entire surface of the leather shall be accessible to the workman and yet prevented from coming into contact with anything that would impair or damage the finish. For purposes of illustration, I have shown the setting-out board 12 with leather 13 thereon, laid at its opposite ends outside the leather upon horses 18, 18, but this is only one of many different ways in which the boards could be supported for finishing the leather.

After the desired finishing operations have been performed upon the leather, it is taken off of the setting-out board upon which it has remained during its entire setting-out drying and finishing because of its adhesion to said board by reason of the setting-out thereon. Great saving in time and labor of handling the leather is effected by my improved process, besides the advantages above recited.

In case any kinds of leather, because of the thickness, weight or other peculiar properties of the leather, should not adhere to the setting-out board sufficiently to withstand handling or drying or the finishing processes, a little adhesive, such as paste or the like, can be used between the setting-out board and piece of leather which is set-out thereon. Of course such adhesive, if necessary at all, should not be strong enough to prevent ultimate removal of the leather from the setting-out board without damage, and it is not likely that it would ever be necessary to use any adhesive for the entire surface of the piece of leather, but only along the margins or edges of the side of the leather next to the setting-out board.

Having thus described the invention, what I claim is—

1. The herein-described method of treating leather, which consists in setting-out the leather upon a setting-out surface while wet, thereby causing adhesion of the leather to said surface in a stretched condition, drying said leather while thus set-out upon and adhering to said surface, and japanning or otherwise finishing the leather while so dried and set-out upon and adhering to said setting-out surface.

2. The herein-described method of treating leather, which consists in placing a thin flat board upon a support, setting-out the leather upon said board while wet, thereby causing adhesion of the leather to said board in a stretched condition, removing said board from said support with the leather still set-out thereon, drying said leather while thus

set-out on and adhering to said board, and japanning or otherwise finishing the leather while so dried and set-out upon and adhering to said setting-out board.

3. The herein-described method of treating leather, consisting in setting-out one portion of a wet piece of leather upon one side or face of a setting-out board and another portion of said piece of leather upon another side or face of said board, the leather being bent over the edge between said sides or faces, thereby causing adhesion of the leather to said board in a stretched condition, drying said leather while thus set-out upon and adhering to said surface, and japanning or otherwise finishing the leather while so dried and set-out upon and adhering to said setting-out board.

4. The herein-described method of treating leather, which consists in setting-out the leather upon a setting-out surface while wet and with an adhesive between said leather and surface, thereby causing adhesion of the leather to said surface in a stretched condition, and drying said leather while thus set-out upon and adhering to said surface until it will retain said stretched condition when removed from the setting-out surface.

5. The herein-described method of treating leather, which consists in placing a thin flat board upon a support, setting-out the leather upon said board while wet and with an adhesive between said leather and board, thereby causing adhesion of the leather to said board in a stretched condition, removing said board from said support with the leather still set-out thereon, and drying said leather while thus set-out and adhering to said board until it will retain said stretched condition when removed from the board.

6. The herein-described method of treating leather, consisting in setting-out one portion of a wet piece of leather upon one side or face of a setting-out board and another portion of said piece of leather upon another side or face of said board, with an adhesive between said leather and board and the leather bent over the edge between said sides or faces, thereby causing adhesion of the leather to said board in a stretched condition, and drying said leather while thus set-out upon and adhering to said surface until it will retain said stretched condition when removed from the board.

7. The herein-described method of treating leather, which consists in setting-out the leather upon a setting-out surface while wet and with an adhesive between said leather and surface, thereby causing adhesion of the leather to said surface in a stretched condition, drying said leather while thus set-out upon and adhering to said surface, and japanning or otherwise finishing the leather while so dried and set-out upon and adhering to said setting-out surface.

8. The herein-described method of treating leather, which consists in placing a thin flat board upon a support, setting out the leather upon said board while wet and with an adhesive between said leather and board, thereby causing adhesion of the leather to said board in a stretched condition, removing said board from said support with the leather still set-out thereon, drying said leather while thus set-out on and adhering to said board, and japanning or otherwise finishing the leather while so dried and set-out upon and adhering to said setting-out board.
- 15 9. The herein-described method of treating leather, consisting in setting-out one portion of a wet piece of leather upon one side or

face of a setting-out board and another portion of said piece of leather upon another side or face of said board, with an adhesive 20 between said leather and board and the leather bent over the edge between said sides or faces, thereby causing adhesion of the leather to said board in a stretched condition, drying said leather while thus set-out 25 upon and adhering to said surface, and japanning or otherwise finishing the leather while so dried and set-out upon and adhering to said setting-out board.
